ATTORNEY.

UNITED STATES PATENT OFFICE.

FRANKLIN T. HAMMERLE, OF DETROIT, MICHIGAN.

SHEET HOLDER.

Application filed March 4, 1924. Serial No. 696,879.

To all whom it may concern:

Be it known that I, FRANKLIN T. HAMMERLE, a citizen of the United States, residing at Detroit, in the county of Wayne and State of Michigan, have invented certain new and useful Improvements in Sheet Holders, of which the following is a specification.

My invention relates to sheet holders and more particularly to devices of this character adapted to releasably hold sand paper, dust cloths, shoe polishing cloths and other similar materials.

The objects of my invention are to provide means adapted to enable the user of sand paper, dust cloths, shoe polishing cloths and other similar articles to conveniently hold the same; to provide means adapted to enable a user of the device to quickly install thereon and remove therefrom the material intended for use; and to provide a sheet holder adapted to minimize the waste of such materials as may be used thereon.

My invention consists in providing a block having rounded ends and having a clasp secured adjacent each of said ends and on top of said block; in providing conveniently operated clasps each of which comprises a pair of spaced apart pointed pins extending outwardly and longitudinally of said block and having their ends adjacent one of said rounded ends; in providing a metal base plate between said pins and combinedly fixed to said pins and said block; in providing a clamping frame comprising a pair of spaced apart rods extending longitudinally of said block and slightly curved outwardly and having their inner and outer ends bent inwardly and connected with spaced apart inner and outer rods integral therewith and extending transversely of said block and means for linking said inner transverse rod of said frame with the inner ends of said pins; in providing a metal band connecting said longitudinal rods and slideable thereon and means for securing said clasp in closed position comprising an outwardly extending lug having an ear integral therewith and extending at right angles thereto, said lug fixed to said base plate and adapted to be engaged by said metal band.

My invention further consists in the parts and in the combination and arrangement of parts as herein set forth and claimed.

In the drawings:

Fig. 1 is a plan view of my invention showing my clasps in closed position;

Fig. 2 is a part section and part side elevation of the same;

Fig. 3 is an end elevation of my invention;

Fig. 4 is an enlarged side elevation showing the block broken away and the clasp in open position;

Fig. 5 is a perspective view of the connecting plate;

Fig. 6 is a perspective view of the invention showing the clasps in closed position;

Fig. 7 is a perspective view of the clasp pins;

Fig. 8 is a perspective view of the metal band;

Fig. 9 is a perspective view of the base plate;

Fig. 10 is a perspective view of my invention showing a shoe polisher attached thereto; and

Fig. 11 is a perspective view of the clasp frame.

In the preferred construction of my invention as illustrated I provide block 1 having rounded ends 1'. At each end of the block is fixed a buckle or clasp 2 having a pair of equal distanced spaced apart pins 3 extending longitudinally of said block and having points 4 projecting outwardly. The pins are secured in position by base plate 5 having ends 6 bent there-around and secured to the block by screws 7. For securely maintaining the pins against movement relative to plate 5 I prefer to solder them to the plate.

Clamping frame 8 has spaced apart rods 9 curved outwardly from block 1 and extending longitudinally thereof and has inner and outer ends 10 and 11, respectively, bent downwardly and slightly inwardly. Rods 13 and 14 integral with rods 9, respectively, connect ends 10-10 and 11-11 and extend transversely of block 1. Inner rod 13 has transverse slot 13' therein caused by forming the clamping frame from a single bar. Inner end 13 has hinged connection with rod 15 extending transversely of the block and connecting the inner ends of pins 3.

Connecting plate 16 having ends 17 and 18, respectively, bent around inner rod 13 of clamping frame 8 and rod 15 connecting

105

pins 3 may have suitable length for providing proper adjustment of outer rod 14 relative to points 4 of pins 3 when clasp 2 is in closed position.

5 Base plate 5 also has integral therewith lug 19 extending outwardly and having ear 20 bent at right angles thereto and extending outwardly for the purpose of engaging metal band 21 looped around and connecting longitudinal rods 9 thereby maintaining the clasp in closed position as shown in Figs. 1, 2, 3, 6 and 10.

10 Longitudinal rods 9 are curved outwardly to provide sufficient spring in clamping frame 8 for the purpose of retaining outer rod 14 in tension engagement with points 4 when the clamp is in closed position.

15 The operation of the mechanism of my invention is as follows:

20 Assume the clasp is in open position as shown in Fig. 4 and that it is desired to secure a shoe polishing cloth thereto. One end 22 of cloth 23 is pierced by ends 4 of pins 3 whereafter clamping frame 8 is closed by first lowering outer rod 14 downwardly and in engagement with the cloth and beneath points 4 of the pins. Inner rod 13 of the clasp is then lowered in engagement with the block whereupon the lever action 25 of connecting plate 16 connected to inner rod 13 integral with frame 8 and rod 15 integral with the inner end of pins 3, causes outer rod 14 of frame 8 to tightly grip the cloth and hold it securely in engagement 30 with rounded end 1' of block 1. Metal band 35 21 is then slid longitudinally inwardly and in engagement with ear 20 of lug 19 thereby retaining inner rod 13 of the clasp against upward movement and locking the clasp in 40 closed position, as shown in Fig. 10. The other end 24 of the strip of cloth 23 is then tightly drawn around the under side 25 of block 1 and placed in position in the clasp fixed to the other end of the block by the 45 same method as employed for securing end 22 in the clasp as described.

50 I have, therefore, invented an extremely simple, efficient, effective, economical and serviceable device for the purposes intended.

55 An advantage of my invention is that a layer of cloth, sand paper or other similar material may be clamped thereon and the complete strip excepting the small portions at the end in engagement with the clasp may be utilized without waste.

60 The usual method of manually sanding surfaces is to place a strip of sand paper upon a rectangular block and hold the sides or ends of the sand paper against the sides 65 of the block by the use of the thumb and fingers. This operation is not only very tiresome but also involves considerable waste of sand paper inasmuch as it is impossible to retain the paper in close contact 70 with the block and when sanding the sur-

75 face the sand paper sometimes becomes crumpled and broken thereby rendering the same unfit for use as well as producing a marred or rough surface on the article being sanded. It is then usually necessary to discard the strip of sand paper and substitute therefor a new piece.

80 By the use of my sheet holder many materials may be securely held in position for various purposes.

85 Another advantage of my invention is that my clasp is so constructed that it will securely retain materials of various width and without regard to the width of the clasp itself.

90 My invention is capable of some modification without departing from its scope or spirit as defined in the claims.

95 What I claim as new and desire to secure by Letters Patent is:

1. In a sheet holder, a block having ends, a clasp fixed to the top and adjacent an end of said block, said clasp comprising a pair of spaced apart pins extending longitudinally of said block and having their inner ends connected with a rod extending transversely of said block, a base plate intermediate said pins and fixed thereto and fixed to said block, a clamping frame having its ends bent downwardly and having its inner end linked to said rod, the opposite end of said frame adapted to be retained under said pins when in clamping position and means for holding the frame in closed or clamping position.

100 2. In a sheet holder, a block, clasps fixed to said block adjacent each end thereof, each of said clasps comprising a pair of spaced apart pins having pointed ends and extending longitudinally of said block and having their inner ends connected with a rod extending transversely of said block, a base plate intermediate said pins and fixed thereto, said plate being fixed to said block and having an angular lug on the inner end thereof, and a clamping frame having its ends bent downwardly and having its inner end linked to said rod, the opposite end of said frame adapted to be retained under said pins when in clamping position, and a 105 slidable member on said frame adapted to be moved beneath said angular lug to hold the frame in clamping position.

110 3. In a sheet holder, a block, clasps fixed to said block adjacent its ends, each of said clasps comprising a pair of spaced apart pins having pointed ends and extending longitudinally of said block and having their inner ends connected with a rod extending transversely of said block, a base plate intermediate said pins and fixed thereto, said plate being fixed to said block and having an outwardly extending angular lug, a 115 clamping frame having its ends bent downwardly and having its inner end linked to 120

125 130

said rod, and means adapted to cooperate with said angular lug for holding said frame in closed position, the opposite end of said frame adapted to be retained under 5 said pins when in clamping position.

4. In a sheet holder, a block, a buckle fixed to said block at one end thereof, said buckle comprising a base plate fixed to said block, a pin fixed to said plate and having 10 a point adjacent one end of said block, a clamping frame linked to said pin and having its outer end adapted to engage said pin adjacent said point when said buckle is

in a closed position and means for holding said frame in clamping position. 15

5. In a sheet holder, a block, a buckle comprising a pin fixed to said block and extending longitudinally thereof and having a point adjacent said end, a clamping frame, a link pivoted at its opposite ends to 20 said pin and the inner ends of said frame, said clamping frame having its outer end adapted to engage said pin when said buckle is in a closed position.

FRANKLIN T. HAMMERLE.
